ATTY

UNITED STATES PATENT OFFICE

GEORGE B. HEATHER, OF WEST HAVEN, CONNECTICUT, ASSIGNOR TO THE WIRE NOVELTY MANUFACTURING COMPANY, OF WEST HAVEN, CONNECTICUT, A CORPORATION OF CONNECTICUT

BUTTON LOOP

Application filed February 20, 1930. Serial No. 429,949.

This invention relates to button loops particularly adapted for use on garment straps, the loop being specially adapted to be suspended at the end of a strap loop in readiness to be clipped over a button the shank of which may be urged from a button-receiving loop into a smaller retaining loop from which it cannot be unintentionally withdrawn.

The objects of the invention are to provide, 10 by bending a piece of resilient wire, a reversible button loop of which the wire ends terminate relatively crossed within a loop; and to provide for such a button loop a novel means for securing the crossed wire ends for 15 a limited relative movement along intersecting paths. With these and other objects in view, as may become apparent from the within disclosures, the invention consists not only of the particular form herein pointed out and 20 illustrated in the drawing but readily admits of certain modifications within the scope of what hereinafter may be claimed.

The character of the invention may be best understood by reference to one illustrative 25 device embodying the invention and illustrated by the accompanying drawing in which the Figure 1 is an upright elevation of the device in normal condition and of which a reversed view would be identical therewith; 30 the Figure 2 is an upright elevation of the device in expanded condition; the Figure 3 is a sectional view of the device on the dotted line "3—3" of the previous figure and a fragmentary view of a part thereof; the Figure 35 4 is a fragmentary view of the device illustrating a modified form of securing means for the wire end portions; and the Figure 5 is a plan view of a clip member before folding.

40 The device is preferably made from a piece of resilient wire of which a middle portion is bent to provide the suspension loop 1 and the arms 2 and 3 depending therefrom to provide the associated loops 4 and 5 in axial alignment and having an intermediate normally contracted throat 6, as illustrated by the Figure 1. The wire end portions 7 and 8 are flattened in the plane of the loops for relative crossing of the end portions in said plane 45 and within the loop 5, as also illustrated by

the Figure 1, each wire end portion being positioned and longitudinally operable along an arc the center 1A of which is taken adjacent the corresponding end of the suspension loop 1, the centers 1A being assumed to be the theoretical points upon which the arms 2 and 3 may be made to swing as the shank S of a button passes the throat 6 and the button loop is thereby caused to expand and then contract. 55 The free extremity of each wire end 7 and 8 is provided with the shoulder 9 of which one is best illustrated by the fragmentary view of the Figure 3. Each shoulder 9 is adapted for engagement with the other of the wire ends to limit the movements of the wire ends 60 7 and 8 along their intersecting paths in the plane of the loops upon reaching the positions illustrated by the Figure 2. A link member 10 encompasses the wire ends 7 and 8 at their intersection to secure the ends 7 65 and 8 against movement of the plane of the loops. 70

In operation, the shank S of a button being urged into the throat 6, as illustrated by the Figure 2, expands the button loop, the end portions 7 and 8 moving along their intersecting arcs of movement and relatively sliding within the link 10, the shoulders 9 limiting such movements. Upon the passing of the shank S into the loop 5 the resiliency of the 75 wire is relied upon to return the button loop to its normal condition, the end portions 7 and 8 providing a shank-seat of cam action 80 operable by shank pressure to maintain a contracted or closed throat 6, as illustrated 85 by the Figure 1.

The Figures 4 and 5 illustrate a modification of the securing means for the ends 7 and 8, the modified means being illustrated in the form of a clip member 10A the plan view 90 of which is illustrated by the Figure 5. The clip 10A is folded along the lines 10B to form a member having the spaced walls 10C adapted to enclose the ends 7 and 8, the inner surface of each wall being provided with a diagonal extending channel depression 10D adapted to receive an end portion 7 or 8 for sliding movement therein, the clip providing the seat 10E for the shank S, as illustrated 95 by the Figure 4.

The button loop in both forms being reversible is adapted to be mounted upon a strap to prominently display the front elevation thereof, as illustrated, or an opposite elevation not illustrated by reason of the fact that both elevations are identical.

I claim:—

1. A button loop comprising a resilient wire bent to form associated loops in axial alignment, the loops having an intermediate restricted throat portion and the end portions of the wire extending relatively crossed within a loop along intersecting arcs described by the end portions upon the expansion and contraction of the loops; means provided by the end portions to limit their relative movement in the plane of the loops; and an enclosing member securing the end portions against relative movement out of the said plane.
2. A button loop comprising a resilient wire bent to form associated loops in axial alignment, the loops having an intermediate contracted throat portion and the end portions of the wire extending relatively crossed within a loop along intersecting arcs described by the end portions upon the expansion and contraction of the loops, the end portions thus providing a seat for the shank of a button; means provided by the end portions to limit their relative movement in the plane of the loops; and an enclosing member securing the end portions against relative movement out of the said plane.
3. A reversible button loop comprising a piece of wire of which a middle portion is bent to form a suspension loop having depending resilient arms cooperating to provide associated loops in axial alignment, the loops having an intermediate contracted throat portion and the end portions of the wire being flattened in the plane of the loops, relatively crossed, and extended within a loop and along arcs described by the movements of the end portions of the resilient arms, the free extremity of the end portion of each arm having a shoulder engageable with the end portion of the other arm to limit the movements of the arms along said arcs; and an enclosing member securing the wire end portions against relative movement out of the said plane.

GEORGE B. HEATHER.
